DESCRIPTION

U.S. PATENT DOCUMENTS

FIG. 1 is a perspective view of the motorcycle drink holder of
the present invention.

D346,996 S * 5/1994 Blackburn D12/411
D423,884 S * 5/2000 Greenwood D7/620
6,059,245 A * 5/2000 Hermansen et al. 248/311.2
6,227,511 B1 * 5/2001 De Costa 248/311.2
D449,814 S * 10/2001 Guertin D12/411
D461,996 S * 8/2002 Liao D7/620
D484,087 S * 12/2003 Cheng et al. D12/420
D526,952 S * 8/2006 Stahel et al. D12/411

FIG. 2 is a first side elevation view thereof, a second, opposite
side being a mirror image of the first side.

FIG. 3 is a third side elevation view thereof.

FIG. 4 is a fourth side view thereof, the fourth side being
opposite the third side.

FIG. 5 is a top view thereof; and,

FIG. 6 is a bottom view thereof.

A support basket of the motorcycle drink holder is shown in
broken lines and forms no part of the claimed design.
